SEWING MACHINE

Norman V. Christensen and Charles F. Rubel,
Chicago, Ill., assignors to Union Special
Machine Company, Chicago, Ill., a corporation
of Illinois

Application January 25, 1936, Serial No. 60,764

7 Claims. (Cl. 112—197)

This invention relates to sewing machines; and it has reference more particularly to a chain stitch sewing machine of the type wherein the rotary main or driving shafts from which the needle, looper and feed mechanisms all derive their movements are journaled in horizontal arms overhanging flat oblong bed plates or work supports. Such machines are extensively used in the manufacture of bags of burlap, canvas and the like as well as in other connections.

The aim of our invention is to enable operation of sewing machines of the type specifically referred to at higher speeds than possible heretofore, with a view toward obtaining increased production from them.

This objective we realize in practice, as hereinafter more fully described, by utilizing light rotary parts to the utmost extent, and translating the rotary motion of such parts into reciprocating motion at points or regions local to those elements (e. g. the needle, looper or loopers, feed elements, etc.) which require reciprocation through provision of correspondingly light, structurally-refined intermediate connections which are dynamically balanced and smooth in their action so that noise, vibration and wear are reduced to a minimum.

Other objects and attendant advantages will appear from the following detailed description of the attached drawings, wherein Fig. I is a longitudinal sectional view of a top rotary shaft flat bed sewing machine conveniently embodying our invention.

Fig. II is a view of the machine in end elevation looking from the left of Fig. I.

Fig. III shows the needle arm of the machine in plan; and

Fig. IV is a plan sectional view of the machine taken as indicated by the arrows IV—IV in Fig. I.

As herein illustrated, the frame of our improved sewing machine comprises a flat horizontal oblong bed plate or work support 1, with an integrally formed hollow standard 2 upstanding from one end thereof and sustaining a hollow overhanging arm 3 above said work support, said arm terminating at its free end in a head 4. The machine is primarily designed for mounting upon the top of an operator's table T (Fig. I) with the bed plate or work support 1 substantially flush, and the parts pendant therefrom projecting down through an opening O in the table. In instances where it is desirable to have the bed plate 1 elevated, or when the machine is to be sustained on a narrow plank or beam as in bag factories, a mounting or base such as shown and described

in a copending patent application Serial No. 58,672 filed on Jan. 11, 1936, by Norman V. Christensen, one of the present applicants, may be used. Journaled in bearing bushings 5 and 6 set into the hollow of the overhanging arm 3 is the main or drive shaft 7 of the machine, the rear end of said shaft extending through the bearing 6 to the exterior where it is provided with a combined hand and belt wheel 8 so that the machine may be operated either manually or by power. As shown, the bearings 5 and 6 have oil ports 9 and 10 which respectively register with vertical oil ducts 11 and 12 accessible at the top of the overhanging arm 3. Guided for vertical reciprocation in upper and lower bushings 13 and 14 set into the head 4, is a vertical bar 15 which carries the needle 16. Up and down movements are imparted to the needle bar 15 by means which includes a dynamically-balanced crank member 17 whereof the crank pin 18 is coupled, by means of a link 19, with a pin 20 projecting rearward from a split collar 21 which is secured to said needle bar near the top within the hollow of the head 4, by a clamp screw 22. The projecting end of the pin 20 is flattened as at 23 to engage a vertical guideway 25 within the hollow head 4, and is thereby steadied in its movements. Free to rotate on the pin 18 is a ball 26 which engages the spherical cavity of a split bearing boss 27 at the lower end of the link 19. The cap piece 28 of the bearing boss 27 is formed with a scoop 29 which dips up lubricating oil from a small well 30 in the bottom of the head 4 and conducts it to the surface of the ball 26, a portion of such oil finding its way to the pin 18 by way of one or more radial ducts 31 in said ball. The described construction of the link 19 constitutes one of the features of the present invention and is advantageous in that said link and its connections are rendered self-aligning, self-oiling and smooth acting, with preclusion of binding and heating of the end bearings of said link when the machine is operated at high speeds. If there should be any tendency of either one of the bearing surfaces of the ball 26 to stick, the other of said surfaces will obviously continue to function as a pivot.

The vertical presser bar 32 of the machine is guided near the bottom in a pendant bearing projection 33 of the head 4, and is held against rotation through engagement of the lateral projection 34 of a collar 35 thereon, in a vertical guide 36 at one side of said head. The upper end of the presser bar 32 is confined to slide in a screw bushing 37 threaded into the upper part of the head 4, said bushing being longitudinally

slotted as at 38. The presser bar 32 is acted upon by a double leaf spring 39, of which the forward end extends through an opening 40 in the back of the head 4 (Fig. III) and into the slot 38 of the bushing 37 to engage the rounded top of said bar, see Fig. II. The rear end of the spring 39 is apertured as shown in Fig. III to engage an anchorage stud projection 41 on the overhanging arm 8. The pressure of the 10 spring 39 is regulatable by a set screw 42 threaded in a bracket lug 43 at the top of the arm 3; and a jam nut 44 functions as a means for holding the set screw in adjusted positions. Due to the influence of the leaf spring 39 upon the bar 15 32, the presser foot 45 at the lower end of the latter is maintained in yielding engagement with the fabric being sewed in the machine.

In order that the presser foot 45 may be raised clear of the work support 1 when desired or 20 required, a lifting latch lever 46 is provided, said lever being fulcrumed to swing about a screw 47 engaged in the front of the head 4, and having a cam surface 48 to coact with a stud projection 49 on the collar 35 affixed to the presser 25 bar 32, see Fig. II.

Extending longitudinally of the machine beneath the work support 1 in parallel relation with the main shaft 7 is a transmission shaft 50, which, at its rear end, is journaled in a bushing 30 51 set into the front wall 52 of a lubricant sump 53 integrally formed with, and depending from said work support. As shown in Fig. I, the lubricant sump 53 is in direct communication with the hollow of the standard 2, and closed at the 35 bottom by a removable plate 55. The shaft 50, it will be noted, extends into the lubricant sump 53 and to its end is secured a helical gear pinion 56, the hub 57 of which abuts one end of the bearing bushing 51 while a collar 58 abuts against 40 the other end of said bushing to hold said shaft from shifting endwise. The gear pinion 56 is driven, through an intermeshing idler gear wheel 59, from a helical gear pinion 60 secured on the main shaft 7 directly adjacent the bearing 6 of 45 the latter. The idler gear 59 is free to rotate on a fixed transverse shaft 61 within the hollow of the standard 2, and the thrust thereof in opposite directions is opposed by collars 62 and 63 on said shaft 61 abutting opposite faces of 50 the hub 64 of said gear wheel. The gear train 56, 59 and 60 is lubricated through splash oil carried up from a supply within the sump 53. In practice, the idler gear 59 is made from suitable 55 sound and wear absorbing material, and is preferably so proportioned with respect to the pinions 56 and 60 that the points of contact thereof with the latter gears constantly change with resultant uniform distribution of the wear. The communication of motion from the upper or 60 main shaft 7 to the lower or transmission shaft 50 is thus effected smoothly, positively and noiselessly. The gear drive herein shown and described is the same in principle and operation as that disclosed in applicants' copending application Serial No. 670,186 filed on May 9, 1933.

At its left hand end (Figs. I and IV), the transmission shaft 50 is integrally formed with a pair of spaced crank heads 65, 66 with a connecting ball crank pin 67, from which the looper 70 mechanism of the machine receives its movements as will be presently explained. The terminal head 65 has a socket to receive the contiguous end of a supplemental shaft 68 which is made fast by screws 69. As shown in Fig. IV, 75 the supplemental shaft 68 is journaled in spaced

pendant bearing lugs 70, 71 of the work support 1, and, in effect, is a coaxial continuation of the transmission shaft 50. Incident to assembling the machine, the collar 58 and the bushing 51 are mounted on the shaft 50 and the right hand end of the latter is inserted through the bearing boss 72 on the oil sump 53, whereupon said bushing is pushed into place and secured by the set screw shown at 73, see Fig. I. The construction of the lower shaft of the machine from the two parts 50 and 68 as shown and described is advantageous in that it facilitates assembling of the machine, and also in that it affords a separable crank 67 at the juncture between said sections. 15

Cooperating with the needle 16 beneath the work support 1 of the machine, is a looper 74 which is carried by a vertical arm 75 fulcrumed on a stud 76 projecting from the looper rocker 77 which is secured by set screws 78 to a rock 20 shaft 79 having its ends journaled in bushings 80 and 81 respectively set into the bearing lugs 70 and 71. The shaft 79 is rocked through the medium of an arm 82 clamped thereto and connected to the strap 83 of an eccentric 84 on the 25 supplemental shaft 68, see Figs. I and IV, with resultant impartation to the looper of its needle avoiding movements. The holder or carrier 75 for the looper 74 is oscillated about the fulcrum 76 in the performance of its loop taking functions through a horizontal link 85 which has split bearings 86 and 87 at its opposite ends respectively engaging a ball stud 88 on said carrier 75 and a similar ball stud 89 on an arm 90 extending upward from an oscillating sleeve 91. As shown, this sleeve 91 is affixed to a transverse rock shaft 92 whereof the ends are journaled in bearing bushings 93, 94 set into spaced lateral projections 95, 96 of the bearing lug 71 hereinbefore referred to. The oscillating sleeve 91 also has a horizontal arm 97 which terminates in a ball end 98 and which is coupled with the crank pin 67 on the transmission shaft 50, by a link 99 also formed with split bearing ends 100, 101, to respectively engage said ball and the crank pin. By employing balanced parts with ball joints in the looper mechanism just described, and through provision of the crank pin 67 in lieu of an eccentric such as is ordinarily used in machines of this type, friction and wear is reduced to a minimum so that the movement of the mechanism is rendered smooth and easy and noiseless. 30

The means provided for progressively advancing the fabric in the machine includes a feed dog 102 which, as shown in Fig. II, is secured, with capacity for vertical adjustment, to a feed bar 103 by means of a screw 104. Fixed in a boss 105 at the rear end of the feed bar 103, is a transverse pin 106 whereof the ends engage spaced bearing bosses 107, 108 of a yoked rocker 109, which, in turn, is secured to a rock shaft 110 whereof the ends are journaled respectively in the bearing 111 of the lug 70 and another bearing lug 112 pendant from the work support 1, said rock shaft being held against shifting axially by collars 113, 114 thereon which respectively abut the lugs 111 and 112 at their inner sides, see Fig. IV. Secured to the outer end of the rock shaft 110, preferably by welding, is a horizontal arm 115 which reaches forwardly and which at its outer end has pivotal connection at 116 with the lower end of a vertical link 117 whereof the upper end is split to clamp a bushing 118 engaging a crank pin 119 on a crank disk 120 affixed 75

to the outer end of the supplemental shaft 68. Thus, during the rotation of the supplemental shaft 68 back and forth feed movements are induced in the feed dog 102. The pin 119 is radially adjustable on the crank disk 120 so that the feed stroke of the dog 102 can be varied. The lift movements are imparted to the feed dog 102 by means of an eccentric 121 on the supplemental shaft 68, the strap 122 of which is pivotally connected at 123 to the downwardly and forwardly curved arm projection 124 of the feed bar 103, see Fig. II. The feed mechanism just described is generally similar to that featured in U. S. Patent No. 1,817,727 to Wohlpert, and, 15 is hereinafter claimed only in combination with the other component and cooperating mechanisms of the machine. It is to be particularly noted however that in the present instance, the feed rocker shaft 109 passes through a bearing in 20 the lug 111 disposed between the feed rocker 109 and the arm 115. This arrangement is advantageous in that it precludes exertion of side thrust or torsion against the feed rocker 109 and thus eases the action of the feed mechanism.

25 In order that tight stitches may be formed by the machine, there is provided a nipper or intermittent tension means for the needle thread, this means being shown in Fig. I as comprising a vertical sleeve 125 which is fast in a boss 126 at the 30 top of the overhanging arm 3, and which is surmounted by a regulatable tension device 127 adapted to be actuated by an eccentric 128 on the main shaft 7 through a thrust pin or plunger 129 guided in said sleeve.

35 Also, during the sewing, the slack of the looper thread is absorbed by a take-up device which is generally designated by the numeral 130 in Figs. I and IV. This take-up comprises a rotary cam disk 131 which is secured to the supplemental shaft 68 and which projects through a slot 132 in an inclined guard plate 133 suitably secured beneath the work support of the machine and overreaching said shaft. Fastened to the guard plate 133 by screws 135 is a U-shaped hold-down 45 tongue 136 of wire (between which and the plate, the looper thread passes), and thread guides 137 at opposite sides of the slot in said plate. The rotary take-up just described corresponds in construction and principle of operation with that 50 forming the subject matter of a copending application Serial No. 24,495, filed on June 1, 1935 by Charles S. Thompson.

From the foregoing it will be seen that in our improved sewing machine, we have utilized but 55 two rotating shafts which are interconnected by a gear train drive system, and from which the rotary movements are translated, through light and dynamically balanced anti-friction parts, into reciprocatory movements of the needle, the 60 looper and the feed dog, at regions local to these cooperating elements. In this way, we have effectively avoided strains and restraints in the moving parts such as would result in excessive heating to the advantage that the machine can 65 be operated at much higher speeds than heretofore attainable.

Having thus described our invention, we claim:

1. In a sewing machine, a frame with a work supporting plate and a hollow overhanging arm sustained by a hollow standard at one end of said plate; a rotary shaft journaled within the hollow of said arm; a needle bar confined to vertical reciprocation in a head at the free end of the overhanging arm; a counterbalanced crank at the forward end of the shaft; a crank pin on said
5. In a chain stitch sewing machine, a frame with a work supporting plate and a hollow overhanging arm sustained by a hollow standard at a

crank; and a connection between the needle bar and the pin of the crank including a link, a lateral pivot on said bar in engagement with a boss at one end of the link, a ball free to rotate on the crank pin as an axis and engaging a spherical bearing surface in a boss at the opposite end of the link. 5

2. In a sewing machine, a frame with a work supporting plate and a hollow overhanging arm sustained by a hollow standard at one end of 10 said plate; a rotary shaft journaled within the hollow of said arm; a needle bar confined to vertical reciprocation in a head at the free end of the overhanging arm; a balanced crank at the forward end of the shaft; a crank pin on said 15 crank; and a connection between the needle bar and the pin of the crank including a lateral stud on said bar in engagement with a bearing boss at one end of the link, a ball free to rotate on the crank pin and engaging a spherical bearing 20 surface in a boss at the opposite end of the link, the last mentioned boss having a scoop projection adapted, during rotation of the crank, to scoop up oil from a well within the head for lubricating the ball and the crank pin. 25

3. In a chain stitch sewing machine, a frame with a work supporting plate and a hollow overhanging arm sustained by a hollow standard at one end of said plate; a pair of longitudinal shafts, one journaled within the hollow arm, and 30 the other journaled beneath the work supporting plate; a train of intermeshing gear wheels forming the drive connection between the two shafts, said gear wheels being enclosed in the hollow of the frame standard and a communicating oil 35 sump pendant from the work support; a needle bar confined to vertical reciprocation in a head at the free end of the overhanging arm; a cooperative looper, and a feed element below said work support; means adjacent the forward ends 40 of the two shafts whereby their rotary movements are converted respectively into reciprocatory movements of the needle bar, and into oscillatory and reciprocatory movements of the looper and the feed dog; a tensioning device for 45 the needle thread; and a rotary cam on the upper of the two shafts for actuating the tensioning device to intermittently apply tension on the thread. 50

4. In a chain stitch sewing machine, a frame with a work supporting plate and a hollow overhanging arm sustained by a hollow standard at one end of said plate; a pair of longitudinal shafts, one journaled within the hollow arm, and the other journaled beneath the work supporting plate; a train of intermeshing gear wheels forming the drive connection between the two shafts, said gear wheels being enclosed in the hollow of the frame standard and a communicating oil sump pendant from the work support; 55 a needle bar confined to vertical reciprocation in a head at the free end of the overhanging arm; a cooperative looper, and a feed element below said work support; means adjacent the forward ends of the two shafts whereby their rotary movements are converted respectively into reciprocatory movements of the needle bar, and into oscillatory and reciprocatory movements of the looper and the feed dog; and tension devices 60 respectively for the needle and looper threads controlled by rotary means respectively on the upper and lower shafts. 65

5. In a chain stitch sewing machine, a frame with a work supporting plate and a hollow overhanging arm sustained by a hollow standard at 70

one end of said plate; a pair of longitudinal shafts, one journaled within the hollow arm, and the other journaled beneath the work supporting plate; a train of intermeshing gear wheels 5 forming the drive connection between the two shafts, said gear wheels being enclosed in the hollow of the frame standard and a communicating oil sump pendant from the work support; a needle bar confined to vertical reciprocation in a 10 head at the free end of the overhanging arm; a cooperative looper, and a feed element below said work support; means adjacent the forward ends of the two shafts whereby their rotary movements are converted respectively into reciprocating 15 movements of the needle bar, and into oscillatory and reciprocating movements of the looper and the feed dog; a tensioning device for the needle thread; a rotary cam on the upper of the two shafts for actuating the tensioning device 20 vice to intermittently apply tension on the needle thread; and a rotary tension device for the looper thread actuated from the lower shaft.

3. In a sewing machine, a work-supporting

plate; a needle operated from above the work-supporting plate; complementary stitch-forming mechanism cooperating with the needle below the work-supporting plate; and a longitudinal shaft composed of two axially-aligned sections with a 5 crank formed at one end of one of said sections for actuating the complementary stitch-forming mechanism, and affording connection for the contiguous end of the other shaft section.

7. In a sewing machine, a work-supporting 10 plate; a needle operated from above the work-supporting plate; complementary stitch-forming mechanism cooperating with the needle below the work-supporting plate; and a longitudinal shaft composed of two axially-aligned sections 15 with a crank formed at one end of one of said sections for actuating the complementary stitch-forming mechanism, and having a socket within which the contiguous end of the other shaft section is received and secured. 20
